(57) **CLAIM**

The ornamental design for an ultrasonic cleaning machine, as shown and described.

DESCRIPTION

FIG. 1 is a front, left and top perspective view of an ultrasonic cleaning machine, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another front, left and top perspective view of the ultrasonic cleaning machine in another state.

The broken lines depict portions of the ultrasonic cleaning machine that form no part of the claimed design.
